UNITED STATES PATENT OFFICE.

GEORGE LEACHMAN, OF SEBRING, OHIO.

DESIGN FOR A CUP.

49,189.

Specification for Design.

Patented June 13, 1916.

Application filed March 15, 1916. Serial No. 84,495. Term of patent 7 years.

To all whom it may concern:

Be it known that I, GEORGE LEACHMAN, a citizen of the United States, and a resident of Sebring, in the county of Mahoning and State of Ohio, have invented a new, original, and ornamental Design for a Cup, of which the following is a specification; reference being had to the accompanying drawing, forming part thereof, and in which:

vertical section of a cup illustrating my new design.

I claim:

The ornamental design for a cup as shown.

GEO. LEACHMAN.

Witnesses:

H. R. EWING,
ELMER G. MORLEY,
WALTER LUGINBUHL.
